LOADING FORK

Julius L. Shumaker, Martel, Ohio

Application February 2, 1939, Serial No. 254,275

7 Claims. (Cl. 294—124)

This invention relates to loading forks and more particularly to a releasable loading fork adapted to be used with an elevating means.

An object of this invention is to provide a loading fork which may be used for loading various articles and which may be dumped or unloaded by release of a locking means forming part of the device.

Another object of this invention is to provide a loading fork of this kind which includes a handle which may be used to project the fork into the material which is being loaded thereupon and which may be held manually against dumping until the fork has been elevated and then swung to the desired location where the fork may be dumped or unloaded.

A further object of this invention is to provide a loading fork of this kind wherein the fork is substantially balanced on a clevis or lifting means so that the person holding the handles of the device may readily maintain the fork in a filled condition until the fork has been swung to the dumping or unloading position whereupon the releasing means may be operated to release the fork for unloading.

To the foregoing objects and to others which may hereinafter appear, the invention consists of the novel construction, combination and arrangement of parts as will be more specifically referred to and illustrated in the accompanying drawing wherein is shown embodiments of the invention, but it is to be understood that changes, variations and modifications may be resorted to which fall within the scope of the invention as claimed.

In the drawing:

Figure 1 is a detail side elevation partly broken away and in section of a loading fork constructed according to an embodiment of this invention, 40

Figure 2 is a sectional view partly in top plan taken on the line 2—2 of Figure 1,

Figure 3 is a fragmentary sectional view taken on the line 3—3 of Figure 2,

Figure 4 is a fragmentary sectional view taken 45 on the line 4—4 of Figure 3, and

Figure 5 is a fragmentary sectional view taken on the line 5—5 of Figure 2.

Referring to the drawing, the numeral 10 designates generally a loading fork which comprises a plurality of tine members 11 which are preferably constructed out of material which is substantially T-shaped in transverse section and these tine members 11 are provided with a relatively straight body portion 12 and an upwardly curved rear portion 13. The upwardly curved

rear portions 13 of the tines 11 are secured together by means of a transversely disposed angle bar 14 which may be welded or otherwise fixedly secured to the upwardly bent portions 13 of the tines.

The fork 10 at each side thereof is provided with a bracing member 15 which is secured at its rear end to the upper rear portion of the tines and at its forward end to a tine as by welding, rivets or the like as indicated at 16.

The tines 11 are also secured to a transversely extending angle bar 17 which is welded to the stem portions 18 of the tines and a shaft or elongated bolt 19 extends through the angle formed by the angle member 17. The shaft or bolt 19 is secured to the forward end of a U-shaped handle or frame member 20 which is formed in the present instance out of tubular material and is provided at the free ends of the parallel legs thereof with flattened or bearing portions 21 through 20 which the bolt or shaft 19 extends.

The handle or frame 20 is provided on the upper side thereof at a point intermediate the ends of the parallel legs 22 thereof with an upwardly offset bar 23 provided with downwardly extending opposite end portions 24 terminating in base portions 25 which are adapted to be secured as by fastening members 26 to the parallel legs 22. The bar 23 constitutes a combined guide retainer and stop element for a slidably mounted fork locking bar 27 which extends transversely of the two legs 22 of the frame 20 between the legs 22 and the bars 23 and is provided with downturned end portions 28 arranged against the outer sides of the legs 22. A guide or bar operating rods 29 are slidable through the guide members 30 fixed to the inner sides of each leg member 22 and the rods 29 are provided with right angularly disposed inner end portions 31 forming handles which are normally disposed forwardly 40 or in spaced relation to the bight 32 of the frame 20. The forward end of each rod 19 is secured as by a fastening means 33 to the locking bar 27 and a spring 34 is positioned about the rod 29 and at one end bears against the adjacent end 45 of the guide member 30 while at the other end the spring 34 bears against a collar or boss 35 which is fixed to the rod 29. The springs 34 normally urge the locking bar 27 forwardly to a locking position.

The fork 10 at each side thereof is provided with a cam member 36 secured to the arcuate portion 13 of the end tine members and a keeper or rearwardly projecting bar 37 is secured to each side of the fork 10 thereby providing a space 38 55

between the keeper member 37 and the upper end of the cam 36 within which the locking member 27 is adapted to engage so as to thereby hold the fork against rocking movement up or down relative to the frame 20.

The fork 10 is elevated through the medium of a clevis generally designated as 39 which comprises a pair of C-shaped portions 40 which are pivotally secured at one end on the shaft or bolt 19. The opposite end of the said members 40 are connected together by a V-shaped connecting member 41 and a transversely extending bracing bar is secured against the lower or divergent ends of the V-shaped member 41. Preferably, a bracing bar 43 is secured within the channel formed by the material of which the clevis 39 is constructed and a ring 44 is mounted about the apex of the V-shaped member 41 and is adapted to receive a sheave 45 which may be connected to a suitable elevating means so that the fork may be swung from a loading to an unloading position. Preferably, the clevis 39 is constructed of a single bar which is substantially U-shaped in transverse section with the channeled portion thereof outermost.

In the use and operation of this loading fork during the loading of the fork, the fork member 10 is adapted to be locked relative to the handle or frame 30 with the locking bar 27 engaged in the keeper formed by the bar 37 and the upper end of the cam member 36. The tines 11 may be projected into the pile of material and then the fork may be elevated by the elevating cable or member 46 which is trained through the sheave 45. The loaded fork may then be swung to the desired location with the operator of the fork grasping the frame or handle 20 so as to maintain the fork 10 in a substantially horizontal and loaded position. When it is desired to unload the fork 10, the locking bar 27 may be pulled rearwardly to a released position against the tension of the springs 34 by pulling the handles 31 rearwardly. This will permit the fork 10 to rock downwardly and forwardly on the shaft 19. In the present instance, the locking bar 27 is provided with two locking bar operators 29 and two handles 31 but it will be understood that if desired, the two handles 31 which confront each other may be connected together so that the bar 27 may be pulled rearwardly with only one hand. The clevis 39 may also be provided with an extension at the upper end thereof so as to position the ring 44 in a plane forwardly of the shaft 19. This may be done where the material which is being loaded is relatively heavy and will have a tendency to tip or tilt the fork forwardly where a small clevis is used.

A fork has been actually constructed according to this invention and from experiments has been found to be more efficient than forks at present available or in use and this loading fork will permit the quick loading or unloading of suitable material as the fork may be suspended from the elevating member 46 and merely projected into the material by the operator who grasps the frame 20 and subsequently merely holds the fork 10 against unloading in the event the forward portion of the fork is unduly loaded. The unloading operation can be effected easily and quickly by pulling the locking bar 27 rearwardly so that the fork 10 will freely swing to an unloading position similar to that shown in Figure 1.

As will be noted from the drawing, the keeper member 37 projects rearwardly a sufficient distance from the rear edge of the cam 36 so that

when the fork 10 is swung downwardly to a locked or loading position, the projecting portion of the keeper member 37 will serve as a limiting means to prevent the locking bar 27 from riding out past the opening 38 formed between the keeper bar 37 and the upper end of the cam 36.

What I claim is:

1. A loading fork comprising a fork member, a U-shaped handle frame, means pivotally securing said fork member on said frame, a clevis pivotally carried by said fork member, spring-pressed locking means disposed transversely of and slidably mounted on said frame and engageable with the sides of said fork member to releasably hold said fork member against movement relative to said frame and spaced parallel combined guide, retainer and stop elements secured on said frame for said locking means.

2. A loading fork comprising a fork member, a U-shaped handle member, means pivotally securing said fork member to said handle member, spring-pressed locking means mounted on and disposed transversely of said handle member, combined guide, retainer and stop elements secured upon said handle for said locking means and a cam-shaped keeper carried by said fork engageable with said locking means to hold said fork against movement relative to said handle member.

3. A loading fork comprising a fork member, a handle, means pivotally securing said handle to said fork member, a cam member carried by said fork member, a keeper bar secured to said fork member, said keeper bar having a portion thereof spaced from an end of said cam member to thereby provide a lock recess, said bar having another portion thereof projecting rearwardly of the rear edge of the cam member and constituting a guide means for guiding a locking means into said recess, a spring-pressed locking means slidably mounted on said handle, and combined guiding, retaining and stopping means secured to the handle for said locking means.

4. A loading fork comprising a fork member having an upwardly bent rear portion, a handle pivotally carried by said fork member, a segmental cam carried by the upwardly bent portion of said fork member, a keeper bar fixed to said fork member in spaced relation to an end of said cam, a spring-pressed locking means slidably carried by said handle for extension into the space between said bar and cam to lock the fork, and a combined guiding, retaining and stopping means on said handle for the said locking means.

5. A loading fork comprising a fork member, a U-shaped handle pivotally secured to said fork member, said fork member having an upwardly curved rear portion, a pair of spaced apart cam members fixed to the rear side of said upwardly curved portion, a rearwardly projecting keeper bar spaced from an end of each cam member and projecting rearwardly thereof, a locking bar extending transversely between the parallel legs of said handle, guide means carried by each leg of said handle for slidably mounting said locking bar on the handle, releasing means slidably carried by said handle and secured to said locking bar, and resilient means normally urging said locking bar to a locking position.

6. A loading fork comprising a fork member, a U-shaped handle pivotally secured to said fork member, said fork member having an upwardly curved rear portion, a pair of spaced apart cam

members fixed to the rear side of said upwardly curved portion, a rearwardly projecting keeper bar spaced from an end of each cam member and projecting rearwardly thereof, a locking bar extending transversely between the parallel legs of said handle, the opposite ends of said bar being arcuately bent to partially engage about the legs of said handle, guide means carried by each leg of said handle for slidably mounting said locking bar on the handle, releasing means slidably carried by said handle and secured to said locking bar, and resilient means normally urging said locking bar to a locking position.

7. A loading fork comprising a fork member, a U-shaped handle pivotally secured to said fork member, said fork member having an upwardly curved rear portion, a pair of spaced apart cam

members fixed to the rear side of said upwardly curved portion, a rearwardly projecting keeper bar spaced from an end of each cam member and projecting rearwardly thereof, a locking bar extending transversely between the parallel legs of said handle, the opposite ends of said bar being arcuately bent to partially engage about the legs of said handle, guide means carried by each leg of said handle for slidably mounting said locking bar on the handle, a pair of rearwardly projecting releasing members fixed at their forward ends to said locking bar, means slidably mounting releasing members on the legs of said handle, inwardly projecting handles carried by said releasing members, and resilient means normally urging said locking bar to a locking position.
